Primary Examiner — Kevin K Rudzinski*Assistant Examiner* — Evans David Delesline(74) *Attorney, Agent, or Firm* — Daniel M. Cohn(57) **CLAIM**

The ornamental design for a ring cover as shown and described.

DESCRIPTION

FIG. 1 is a perspective view of a ring cover showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 3.

The dash-dash broken lines in the drawings depict portions of the ring cover that form no part of the claimed design. The dot-dash broken lines in FIGS. 1, 3 and 9-10 represent boundaries of the enlarged portions and form no part of the claimed design.
